UNITED STATES PATENT OFFICE.

JAMES E. McHUGH AND ALVIN G. FIELDS, OF EAST ST. LOUIS, ILLINOIS.

ADJUSTABLE SUPPORT FOR BUILT-IN BATHTUBS.

Application filed December 6, 1926. Serial No. 152,831.

Our invention relates to adjustable supports for built in bath-tubs, and, it is a practical device to overcome certain practical objections to, and defects in the present methods of supporting built in bath-tubs.

The object of our invention is to provide an adjustable support upon which a built in bath-tub can rest without becoming displaced after it has once been positioned, thus preventing unsightly cracks between the plaster in the walls and the wall engaging edges of the tub.

A further object of the invention is the provision of a support which is skeleton like in form and upon which the tub is seated and provided with adjusting screws for engagement with one of the horizontally projecting side rims of the tub.

A further object of the invention is the provision of adjustable supports for built in bath-tubs which possess advantages in points of simplicity and efficiency, and, at the same time prove themselves inexpensive in cost of manufacture.

With the above and other objects in view, the invention consists in the novel features of construction and arrangement of parts hereinafter more fully described and finally pointed out in the claims hereto appended.

Referring to the accompanying drawings forming a part of this specification, wherein like characters of reference denote similar parts throughout the several views:

Fig. 1, is a top plan view of a built in bath-tub held in position by our adjustable support.

Fig. 2, is a longitudinal sectional view of the tub shown as resting upon the support.

Fig. 3, is a transverse sectional view of a tub and the support.

Fig. 4, is a perspective view of an adjustable support for built in bath-tubs embodying the features of our invention.

In the drawings, the reference numeral A represents a built in bath-tub having the horizontally projecting rim sections 1, 2 and 3 and the downwardly projecting front skirt member 4.

In carrying out the aim of our invention, we provide an adjustable support for a built in bath-tub, which consists of a pair of L-shaped supporting members each comprising a horizontally disposed base or floor member 5 and an upright arm member 6, which arm members 6 each terminate at their upper end in a laterally directed ear which will prevent any possible displacement

7 and each of which is provided with a screw threaded opening 8 for the reception of suitable screw member 9 having a head 10 upon which the horizontally projecting side rim section 1 is adapted to rest, as clearly shown in Figs. 2 and 3.

The L-shaped supporting members are spaced a suitable distance apart, as shown in Figs. 1, 2 and 4 and the base sections 5 thereof are connected by means of a pair of leveling strip engaging members 11 which are spaced a suitable distance apart, as shown in Figs. 3 and 4, and fixed at their ends to the base members 5 by means of suitable fastening devices 12, such as screws, bolts, or the like.

The leveling strips 13 and 14 which are formed integral with the bottom of the tub A are seated upon the longitudinally disposed leveling strip engaging members, as clearly shown in Figs. 2 and 3, which provides a perfectly level base for the tub to rest upon.

The spaced base members 5 of the L-shaped supports are fixed to the floor 15 under the tub by suitable fastening devices 16 which pass through openings 17 therein to prevent displacement thereof upon the floor while the upright arms 6 thereof are fixed to a wall block, or its equivalent member 18, as shown in Fig. 3 by suitable fastening devices 19 which pass through openings 20 in the uprights 6.

The free, or forward ends of the base members 5 of the L-shaped supporting members are offset downwardly as at 21, so that tile or other finished flooring 22 may be seated thereon and caused to close the crack 23 between the lower edge of the bath-tub skirt and floor, as clearly shown in Fig. 3. The offset ears 21 are each provided with an opening 24 for the passage of a fastening device 25 for anchoring the free ends of the base members 5 to the floor under the finishing tile or other finished flooring 22, as shown in Fig. 3.

After seating the leveling strips 13 and 14 of the tub upon the leveling strip supporting members 11 of the device, the heads 10 of the adjusting screws 9 are so adjusted as to engage the underface of the side rim 2 of the tub, one upon the members 11 and the other upon the screw heads 10, which arrangement permits of the proper leveling of the tub and provides a support therefor which will prevent any possible displacement

of the tub, thus eliminating any possible chance for cracks to appear between the rim sections of the tub and the plastering of the walls, as is manifest.

5 From the foregoing description, it is evident that we provide an adjustable support for built in bath-tubs, which is superior in every respect to the usual method of blocking up the tub until the desired level has 10 been attained, which blocks become displaced with the result that cracks appear between the rim sections of the tub and the plastering of the walls.

15 The many advantages of the herein described invention will readily suggest themselves to those skilled in the art to which it appertains.

20 We do not wish to be understood as having limited ourselves to the specific details of construction shown and described, but desire to have it understood that the invention we have shown in the drawings is merely illustrative, as it is manifest that various minor changes may be made in the exact construction 25 and particular arrangement of parts without departing from the spirit of our invention, hence we reserve the right to make any such changes, or modifications as may fairly fall within the scope of the appended claims when fairly construed.

30 What we claim is:

1. The combination with a built in bath-tub having a laterally projecting rim and leveling strips of a support therefor, said 35 support having spaced parallel leveling strips supports and vertically adjustable rim supporting means.

2. The combination with a built in bath-tub having a laterally projecting rim at its 40 upper edge and spaced leveling strips upon its lower face, of a support therefor, said support comprising a pair of spaced L-shaped members, a pair of spaced connecting members upon which the leveling strips of 45 the tub rest, and adjustable means carried by the L-shaped members for engagement with the underface of the rim of the tub.

3. A support for built in bath-tubs having 50 spaced leveling strips comprising spaced members upon which the leveling strips of the tub are seated, angular members to which said spaced members are connected and ver-

tically adjustable means carried by the angular members upon which the rim of the tub is seated.

55

4. A support for built in bath-tubs comprising a pair of supporting members each having a base section and an upright arm section, tub supporting means connecting the base members and adjustable tub rim supporting means carried by the upright arm sections.

60

5. A support for built in bath-tubs comprising a pair of spaced L-shaped members, screw threaded members carried by the L-shaped members for engagement with the rim of the tub and means connecting the L-shaped members upon which the bottom of the tub is seated.

65

6. A support for built in bath-tubs comprising a pair of spaced L-shaped members for engagement with the rim of the tub, means connecting the L-shaped members upon which the bottom of the tub is seated and said L-shaped members having one end 75 thereof offset downwardly so as to allow the floor to seat thereupon adjacent the lower edge of the front skirt of the tub to conceal the lower edges of the skirt.

70

7. A support for built in bath-tubs comprising a pair of spaced supporting members each having a base member for attachment to a floor and an upright member for attachment to a wall, adjustable means carried by the upright arms for engagement 85 with the rim of the tub and means connecting the base members upon which the bottom of the tub is seated.

80

8. A support for built in bath-tubs comprising a pair of spaced supporting members each having a base member for attachment to a floor and an upright member for attachment to a wall, adjustable means carried by the upright arms for engagement with the rim of the tub, means connecting the base members upon which the bottom of the tub is seated and the free end of said base members being offset downwardly to allow flooring to conceal the lower edge of the skirt of the tub.
